UNITED STATES PATENT OFFICE.

JOHN E. CONZELMAN, OF WEBSTER GROVES, MISSOURI, ASSIGNOR TO UNIT CONSTRUCTION COMPANY, OF ST. LOUIS, MISSOURI, A CORPORATION OF DELAWARE.

WALL CONSTRUCTION.

1,079,112.

Specification of Letters Patent.

Patented Nov. 18, 1913.

Original application filed November 9, 1911, Serial No. 659,298. Divided and this application filed August 7, 1912. Serial No. 713,901.

To all whom it may concern:

Be it known that I, JOHN E. CONZELMAN, a citizen of the United States, residing at the city of Webster Groves, in the county 5 of St. Louis and State of Missouri, have invented certain new and useful Improvements in Wall Construction, (Case B,) of which the following is a specification.

This application is a division and a continuation of one filed by me November 9, 1911, Serial No. 659,298.

This invention relates to concrete building structures, and has for its object to provide a structure in which concrete slabs and 15 columns are united to form a wall having an air-space therein and being particularly adapted for cold storage plants, residences, and the like.

With this object in view, the present invention consists of the novel features of construction and arrangement of parts, as will be hereinafter more fully described and pointed out in the claims.

In the accompanying drawings forming 25 part of this specification in which like numbers of reference denote like parts wherever they occur, Figure 1 is a side elevation of part of a wall embodying this invention and including two columns and wall slabs connected therewith; Fig. 2 is a sectional view on the line 2—2, Fig. 1; Fig. 3 is a sectional view on the line 3—3, Fig. 1; and Figs. 4, 5, 6, and 7 are detailed views of the form of slab with an air-space therein used in this 35 construction.

Each panel of the wall consists of a pair of columns or uprights 1 and a plurality of vertically-disposed slabs 2, the ends of which fit in grooves 3 in the sides of said columns.

Each slab 2 is preferably molded with a rectangular configuration and is formed in two members 4 and 5 which are preferably united integrally, as illustrated in detail in Figs. 4 to 7, inclusive. The member 4 is 45 preferably wider than member 5 and provided with a pair of flanges 6 that is arranged to extend vertically on a face thereof, one flange being located at one end of said slab and the other flange being located at the 50 other end of same. The member 5 is preferably molded with a uniform thickness throughout and is united integrally with the flanges 6 on member 4, in the manner

about to be described, so as to leave an air-space 7 between members 4 and 5.

55

The member 4 is molded first and, when the concrete is poured into the form 8 of any desired construction, in order to form member 5, the member 4 is placed so that its flanges 6 rest on the plastic concrete in said form, as best seen in Fig. 5. The concrete in the form 8 sets integrally with the faces of the flanges 6 on member 4 and thereby unites said member 4 and member 5 integrally, so as to form the slab 2 having an air-space 7 between said member 4 and member 5. The member 4 may be so placed on the member 5 that either the top or the bottom of member 4 extends beyond the top or bottom of member 5, as illustrated in Fig. 70 7, so that, when the slabs 2 are placed one on top of another to form a panel, the ends of said slabs fit in the grooves 3 in columns 1, and each slab joins the slab adjacent thereto by means of a rabbeted juncture. 75 As additional strengthening means reinforcing bars 9 are embedded in member 4, same being located near one surface of said member and others near the other surface thereof. The ends of bars 9 may bend over rods 80 10, which extend longitudinally in flanges 6, and project from the faces of said flanges into member 5, as shown in Fig. 5, or, if desired, the bars 9 may terminate adjacent the ends of member 4 and the bars 10 may 85 be arranged to extend through U-shaped bars 11 in flanges 6, said bars 11 being arranged so that their ends project from said flanges into member 5, as depicted in Fig. 5.

The columns 1 are preferably supported 90 on a foundation 12, which extends underneath the lower slab 2. A rib 13 on said foundation fits in the lower part of the air-space 7 in the lower slab 2 and the members 4 and 5 of said lower slab are preferably 95 arranged so that the bottoms thereof are substantially flush, in order to rest on said foundation, as depicted in Fig. 2. If desired, the adjoining edges of each two adjacent slabs 2 and the ends of said slabs may 100 be "buttered" with grout just previous to the placing of said slabs in position in the wall, so that, when said grout sets, said slabs are united integrally and said slabs and columns 1 are, also, united integrally, thus 105 constituting a monolithic structure. The

bottoms of the lower slabs 2 of each panel may, also, be "buttered" with grout, which, when set, unites the lower slabs and foundation 12 integrally.

5 A wall constructed of slabs having air-spaces therein as hereinabove described is not only light in weight, but renders the space or room inclosed thereby moisture proof. By reason of the slabs 2 being united 10 by rabbeted joints, the junctures are thereby made secure and durable. The slabs and columns coöperate and are interengaged to form a rigid, secure, and lasting structure.

I claim:

15 1. In concrete construction, a series of superimposed slabs, each slab being composed of a pair of side members, one of said members having vertical end flanges and reinforcing bars the ends of which bars project 20 through the end flanges, the other member abutting said end flanges and having the said projecting ends of the bars extending

thereinto whereby said bars serve to provide anchors for the second named slab.

2. In concrete construction, a pair of 25 spaced grooved columns, a series of hollow unitary slabs each composed of a pair of members, one of said members being longer than the other member and having flanges on its inner face and at the ends thereof, the 30 ends of the longer member extending beyond the adjacent ends of the shorter member, the respective ends of the two members extending in the grooves of the columns, the ends of the shorter member being spaced 35 from the respective adjacent bottom walls formed by the grooves of the column to form grout receiving space.

In testimony whereof I hereunto affix my signature in the presence of two witnesses. 40

JOHN E. CONZELMAN.
